[57] **CLAIM**

The ornamental design for a game bird releasing box, as shown and described.

DESCRIPTION

FIG. 1 is a top perspective view of a game bird releasing box showing our new design;

FIG. 2 is a left end elevational view thereof, the right end being the same as the left end shown; and

FIG. 3 is a front elevational view thereof, the rear being the same as the front shown.

FIG. 1

FIG. 2

FIG. 3
